UNITED STATES PATENT OFFICE,

ARTHUR K. WHITELAW, OF WOODRIVER, ILLINOIS.

CONDENSER.

1,237,848.

Specification of Letters Patent. Patented Aug. 21, 1917.

Application filed April 24, 1917. Serial No. 164,106.

To all whom it may concern:

Be it known that I, ARTHUR K. WHITELAW, a citizen of the United States, and a resident of Woodriver, in the county of 5 Madison and State of Illinois, have invented a new and Improved Condenser, of which the following is a full, clear, and exact description.

My invention relates to condensers particularly adaptable for use in connection with crude petroleum. An object thereof is to provide a simple, inexpensive and efficient apparatus which will be economical and increase the yield and the quality of the 15 product.

With the above and other objects in view, the nature of which will more fully appear as the description proceeds, the invention consists in the novel construction, combination and arrangement of parts as herein 20 fully described, illustrated and claimed.

In the accompanying drawings, forming part of the application, similar characters of reference indicate corresponding parts 25 in both views.

Figure 1 is a vertical section of my condenser shown in its relation to the still and submerged surface condenser; and

Fig. 2 is a horizontal cross section.

30 My still is particularly designed for the Burton process of distilling crude petroleum under pressure, but it is also adaptable to other methods of refining petroleum, whether under pressure or otherwise. The 35 apparatus consists of concentric cylinders 3 and 4 mounted vertically. The heads 5 and 6 respectively of the outer cylinder 4 serve also as heads for the inner cylinder 3. The annular space formed between the 40 cylinders is the preheating chamber 7 for the crude oil or distillate fed thereinto through a conduit 8, preferably located near the lower end of the outer cylinder.

The inner cylinder 3 has a conduit 9 near 45 the top thereof constituting an overflow from said chamber 7 into the inner cylinder. It discharges on to a plate 10 carried by a rod 11 mounted concentrically within the inner cylinder 3 from a spider 12 provided

50 near the lower end of said inner cylinder. The said rod 11 carries a series of said plates 10 through its length. The said plates are alternated by centrally-apertured plates 13 secured at the margin to the cylindrical surface of the inner cylinder 3. In consequence, the liquid delivered by the conduit

9 to the first plate drips on to the centrally-apertured plate underlying it, from where the liquid falls on to the next plate 10 therebelow, etc., until it reaches the lower head 60 6, whereat a conduit 14 is provided which connects the inner cylinder with a still 15.

The conduit 14 serves as a vapor conduit from the still to the condenser, and also as a feed to the still for the non-vaporized 65 liquid portions remaining from the liquid which overflows into the inner cylinder, and for the undesirable and heavy fractions carried off by the vapors from the still and interrupted or recondensed by the liquid 70 which overflows into the inner cylinder from the chamber 7.

The upper head 5 of the cylinders is connected by a conduit 16 to a submerged surface condenser 17 wherein the vapors from 75 the inner cylinders are condensed. A direct feed conduit 17 is provided for the inner cylinder 3 whereby oil or distillate can be fed directly into said inner cylinder without a flow through the preheating chamber. 80 The chamber 7 is provided with a drain conduit 18.

The crude oil or distillate entering the chamber 7 is preheated by vapors flowing from the conduit 14 to the inner cylinder. 85 In turn, the liquid in the preheating chamber 7 serves as means for condensing the heavier and undesirable fractions carried off by the vapors from the still. This chamber, further, permits more constant and steady 90 operation at variable atmospheric conditions, from which the inner cylinder is protected by the body of the liquid in the preheating chamber. The large surface presented by the baffles within the inner cylinders facilitates the dissolving of the lighter hydrocarbons present in the liquid flowing through the conduit 9 by the vapors flowing from the still, and also the recondensation of the objectionable parts present 95 in the vapors, which are, therefore, caused to return to the still with the non-dissolved or vaporized fluid coming from the overflow 9.

I claim:

1. A condenser comprising a pair of concentric cylinders forming an annular chamber, means for supplying fluid to the annular chamber, an overflow from the annular chamber into the inner cylinder, said inner cylinder having a vapor inlet, and baffle plates interposed between the overflow and

105

110

the vapor inlet, said inner cylinder having a vapor outlet.

2. A condenser comprising a pair of concentric cylinders forming an annular chamber, means for supplying liquid to the chamber, an overflow conduit from the chamber to the inner cylinder, said inner cylinder having a vapor inlet and a vapor outlet, a series of spaced plates disposed between the 10 overflow conduit and the vapor inlet, and a series of spaced centrally-apertured plates alternating said first-mentioned plates.

3. A condenser comprising a pair of concentric cylinders adapted to be disposed vertically and forming a vertical annular chamber, means for feeding liquid to the annular chamber near the lower end thereof, an overflow conduit from the upper end of the 20 annular chamber into the inner cylinder, said inner cylinder having a vapor inlet near the lower end thereof and a vapor outlet at the top thereof, a series of circular plates disposed concentrically with the inner cylinder and in spaced relation with 25 each other between the overflow conduit

and the vapor inlet, and centrally-apertured plates carried by the inner cylinder, said centrally-apertured plates being alternated by the circular plates.

4. A condenser comprising a pair of concentric cylinders having common heads whereby an inner chamber is formed, said cylinders being adapted to be disposed vertically, means for supplying fluid to the annular chamber near the lower end thereof, 30 an overflow conduit from the upper end of the annular chamber into the inner cylinder, said inner cylinder having a vapor inlet at the lower end thereof and a vapor outlet at the upper end thereof, a spider 35 within said cylinder near the lower end thereof, a rod mounted on said spider concentrically with the inner cylinder, a plurality of circular plates carried by said rod in spaced relation, a plurality of centrally-apertured plates carried by the inner cylinder in alternation to the circular plates, and means for feeding liquid directly into the 40 said inner cylinder.

ARTHUR K. WHITELAW.
